**OPERATOR BRIDGING UNIT FOR METAL
WINDOW SCREENS**

Russell M. Winnan, Miami, and Burton W. Saxtan, Miami Springs, Fla., assignors to American Screen Products Company, Miami, Fla., a corporation of Florida

Application April 13, 1956, Serial No. 578,014

4 Claims. (Cl. 160—95)

This invention relates to window screens and more particularly to an operator bridging unit for screens of the metal frame type.

Heretofore, it has been necessary, where wood frame screens were used with awning type windows, to notch the bottom rail in a fashion to fit over the window operator and its housing. It is impractical to so modify the slender frame of metal screens, because of weakening the bottom rail. An increase in the size of the rail to offset the weakness resulting from a notch, defeats the major objective of a metal frame screen, which is to admit more light and air, by virtue of its slender rail design, than does a wood frame screen. If an appendage such as an angle or a channel is added to one of the rails of a typical metal frame screen, and such appendage only to be notched in whatever manner required to fit over the control-bar housing, thus avoiding impairment of the original inherent strength of the metal frame screen, the screen to which such appendage has been attached presents a number of disadvantages with respect to a screen incorporating the bridge insert. By virtue of its appendage, the screen to which it is attached admits less light and air than does a screen with a bridge insert. An appendage, such as an angle or channel, which incorporates a notch presents greater possibility of injury when being handled than does the solid bridge insert. From the standpoint of production a single frame section design is used when making a screen which incorporates a bridge insert; as opposed to the necessity of producing and attaching an appendage, such as an angle or channel, in the case of screens using such appendage, or the necessity of providing and combining frame sections of different design in cases where such screens incorporate the appendage in the design of the rail to which a separate angle or channel appendage might normally be attached.

Therefore, a primary object of the present invention is the provision of a rigid bridge insert including an appropriately arched portion accommodating the arm and housing of a window operator and having its ends force fitted into adjacent sections of a tubular rail. A distinctive feature of the invention is that it makes possible the use of the same type frame on all sides of the screen on an awning window as would be used, for example, on a casement window.

Another object of the invention is to provide a rigid one-piece insert having arms at either side of the arched body portion to fit into the related ends of tubular screen frame sections, said arms formed at a slightly upward pitch to conform to the bow normally incorporated in the frame. This bow, or bend, in the frame member has a definite tendency to reassert itself after the tubular frame is forced into a straight line to receive the screen cloth. As a result, the frame members of the screen exert constant pull on the cloth and keep it taut.

A further object is to provide an operator housing bridging unit which provides for the use of a continuous spline to assure a firm grip on the screen cloth at all points along the frame section and the bridge.

2

Other objects are, no loss in light or air as compared with the screening of other types of windows; uniformity of appearance of screens on all types of windows in a given room or a given house; the screen itself, viewed separately, presents a pleasant, balanced unit; the notch in the screen is smooth and safe to handle; the hollow screen frame is completely sealed at all points; production is simplified and standardized in that the screen and the cloth are of the same size for a given awning window, whether it be manually operated or push-bar operated; complicated designs of push-bar housings may be easily matched in every detail in the cast insert as opposed to a stamping or a stamped cutout; and finally, the insert actually increases the strength of the screen frame at the notch.

A preferred and practical embodiment of the invention is shown in the accompanying drawings, in which:

Fig. 1 is a detail cross section showing the application of the invention.

Fig. 2 is a detail elevation looking at the inner or room side of the screen.

Fig. 3 is a view like Fig. 2 showing the outer side of the screen with the spline in the curved groove of the bridge body.

Fig. 4 is a room side elevation of the bridge unit detached from the screen.

Fig. 5 is an outer side elevation of the detached unit shown in Fig. 4.

Fig. 6 is an end elevation of the unit.

Fig. 7 is a cross section taken on the line 7—7 of Fig. 5.

Fig. 8 is a cross sectional view taken on line 8—8 of Fig. 2.

Similar references designate similar parts in the several views.

As will be seen from Figs. 1 and 2, the window W is connected by an operator O in the form of a push-rod slidable in the housing H, the latter being fitted within the arched body portion of the operator bridging unit B in the bottom rail R of the screen S.

The bridging unit B is preferably cast in one piece and includes a medial body 1 having at its top side an arched spline receiving groove 2 formed by spaced channel flanges 3—4 projecting laterally from the body at the side of the unit opposite the room side, and also having at its lower side the compound recess 5—6 opening at the bottom edge of the rail and conforming generally with the cross-sectional profile of the operator housing. Obviously, the invention would be the same if the recess 5—6 was curved or of any other profile so long as it accommodated the operator and its housing.

The outer upper edge of the arched body is inset as indicated at 7 to make the outer face of the body flush with the spline receiving bead portion of the tubular screen frame when the bridge unit is in place.

Each end of the body 1 is formed with laterally extending arms 8, which may be conveniently made of channel formation, and have an upstanding vertical flange 9. The channel formation of the arms serves a definite purpose in providing a friction grip against the faces of the screen frame section, as shown in Fig. 8. Moreover, this channel formation offers definite torque resistance to the entire bottom rail of the screen. As will be seen from the drawing, the upstanding flange 9 mates with a groove of the section and is of particular importance because it lends strength to both the force fit of the insert and to the resistance of the entire lower rail assembly to distortion. The arms 8—8 are of less height and less width than the body to compensate for the thickness of the metal in the rail sections F—F', and, where they join the body, shoulders 8^a are provided against which the inner ends of the sections abut. These

arms telescope within the tubular portions of the related rail sections, and the upstanding flange 9 fits into the related groove of the tubular section.

The arms 8 are, as a whole, tilted upwardly at their outer ends, that is, the arms tilt upwardly with respect to any horizontal plane through the medial body when positioned as shown in Fig. 4 or 5. The degree of tilt conforms with the bow or bend put in the frame member for keeping the screen cloth taut.

When the bottom rail of the screen is made up, the arms 8 are inserted in the adjacent inner ends of the rail and the ends of the curved spline groove 2 align with the spline groove of the rail. After the screen cloth is in place, the spline is pushed or pressed into the communicating grooves in the frame sections and body to lock the screen cloth in place. The screen is then ready for installation in a window, and the bridge unit will take care of the operator housing. Although the bridge is usually located midway of the bottom rail of the screen, it will, of course, be understood that it may be shifted toward either side of the center, if the installation requires, and, while the bridge is described as being in the bottom rail, it could be placed in a side rail or the top rail for certain types of casement windows.

The design of the bridge insert provides for the use of a continuous spline 10 to assure a firm grip of the screen cloth at all points. Moreover, the curved spline groove 2 in the body is important, in the respect that when the continuous spline 10 is fitted to the rail, the curved portion augments the frictional lock between the unit and the sections F and F' to prevent the separation of the rail sections which receive the arms 8.

As opposed to a screen using an appendage or attachment at the cutout, a screen incorporating the bridge insert set forth herein offers production advantages because such screen can be made from a single tubular section, the basic shape of the section used at the bottom rail being the same as that used on all other rails of the screen. When an appendage or attachment is added to the bottom rail, such rail, in effect, becomes a different shape, by virtue of such appendage, than the remaining rails common to the sides and top of the screen.

From the foregoing it will now be seen that the present bridging unit fulfills the objectives heretofore set forth. That is to say, a bridging unit of the type set forth herein not only provides uniformity of appearance of screen frames on all types of windows and does not diminish the light or area of the screen, while at the same time avoiding the unbalanced appearance resulting from using a separate angle on the rail and having a notch to clear the operator. As will be readily understood a notched angle, channel, or other member incorporating a stamped notch would of necessity have thin sharp edges which constitute a hazard in handling. Moreover because of the snug force fit of the arms 8 in the related frame sections the rail having the operator will be completely sealed at all points whereas in notching a structural shape it is difficult to maintain

adequate sealing between the screen and the window frame.

We claim:

1. A metal frame screen comprising tubular rails at least one of which includes separate aligned sections, and an operator bridging unit including a medially arched body having a plane outer face and a spline receiving groove at the inner face thereof, arms projecting from each end of the body for insertion into related ends of said tubular sections, and a flange at the upper edge of each arm forming a continuation of the bottom of the spline groove and force fitted into a mating slot on the section to resist distortion of the rail.
2. A metal frame screen comprising tubular rails at least one of which includes separate aligned sections, and an operator bridging unit including a medially arched body having a plane outer face and a spline receiving groove at the inner face thereof, arms projecting from each end of the body for snug insertion into related ends of said tubular sections, said arms being of less vertical height and horizontal width than the body where they join therewith to provide shoulders against which the ends of the telescoped sections abut, and a flange at the upper edge of each arm forming a continuation of the bottom of the spline groove for entering a mating slot on the section.
3. An operator bridging unit for metal window screens having tubular metal frame sections constituting a rail thereof, comprising, a medially arched body having a spline-receiving groove in one face thereof, arms projecting from each end of the body for insertion into related ends of said tubular sections, and a flange at the upper edge of each arm forming a continuation of the bottom of the spline groove.
4. An operator bridging unit for metal window screens having tubular frame sections constituting a rail thereof, said unit enabling the screen in which it is embodied to be inserted in and removed from a window frame without dismantling the unit or the operator, said unit comprising, a one-piece body medially of greater vertical depth than the depth of said screen frame sections and having an unobstructed operator housing accommodating recess opening along an edge thereof and at both sides of the body, arms extending from opposite ends of the body in a plane below the top of said body and adapted to enter related hollow screen sections and means on the body and arms for receiving a continuous spline element to attach the screen cloth to the bridging unit.
